CLAIM

The ornamental design for an illuminated antenna cover, as shown and described.

DESCRIPTION

FIG. 1 is a side perspective view showing a first state in a sequence of an illuminated antenna cover showing our new design;

FIG. 2 is a side view thereof;

FIG. 3 is a bottom view thereof;

FIG. 4 is a side perspective view showing a second state thereof;

FIG. 5 is a side view thereof;

FIG. 6 is a bottom view thereof;
 FIG. 7 is a side perspective view showing a third state thereof;
 FIG. 8 is a side view thereof;
 FIG. 9 is a bottom view thereof;
 FIG. 10 is a side perspective view showing a fourth state thereof;
 FIG. 11 is a side view thereof;
 FIG. 12 is a bottom view thereof;
 FIG. 13 is a side perspective view showing a first state in a sequence comprising a second embodiment thereof;
 FIG. 14 is a side view thereof;
 FIG. 15 is a bottom view thereof;
 FIG. 16 is a side perspective view showing a second state thereof;
 FIG. 17 is a side view thereof;
 FIG. 18 is a bottom view thereof;
 FIG. 19 is a side perspective view showing a third state thereof;
 FIG. 20 is a side view thereof;
 FIG. 21 is a bottom view thereof;
 FIG. 22 is a side perspective view showing a fourth state thereof;
 FIG. 23 is a side view thereof;
 FIG. 24 is a bottom view thereof;
 FIG. 25 is a side perspective view showing a fifth state thereof;
 FIG. 26 is a side view thereof;
 FIG. 27 is a bottom view thereof;
 FIG. 28 is a side perspective view showing a sixth state thereof;
 FIG. 29 is a side view thereof; and,
 FIG. 30 is a bottom view thereof.

The broken lines immediately adjacent to the surfaces with shade lines represent boundaries of the claimed design; all other broken lines show portions of the illuminated antenna cover that form no part of the claimed design.

The claimed design includes gray shaded elements which represent illumination. Within a gray shaded element, the gradations of dark gray to light gray represent illumination of varying brightness or intensity, darker gray shading representing greater brightness and lighter gray shading representing lesser brightness.

In each embodiment, the claimed design sequentially transitions from the first state to the last state in the sequence. The period with which one image transitions to another image forms no part of the claimed design.

In the first embodiment, the gray shaded elements of FIGS. 1-3 and 7-9 represent illumination in a first color, and the gray shaded elements of FIGS. 4-6 and 10-12 represent illumination in a second color.

In the second embodiment, the gray shaded elements of FIGS. 13-15 and 22-24 represent illumination in a first color, the gray shaded elements of FIGS. 16-18 and 25-27 represent illumination in a second color, and the gray shaded elements of FIGS. 19-21 and 28-30 represent illumination in a third color.
